American Radiator & Standard Sanitary Cor-
poration, Pittsburgh, Pa., a corporation of
Delaware

Application April 16, 1953, Serial No. 24,539

Term of patent 14 years

(Cl. D91—3)

To all whom it may concern:

Be it known that I, Walter Baker, Jr., a citizen of the United States, residing at Louisville, State of Kentucky, have invented a new, original, and ornamental Design for a Faucet, of which the following is a specification, reference being had to the accompanying drawing, forming a part hereof.

Figure 1 is a top plan view of a faucet showing my new design;

Figure 2 is a side elevation view thereof; and
Figure 3 is a perspective view thereof.

The dominant features of my design reside in the portions shown in full lines.

I claim:

The ornamental design for a faucet, substan-

tially as shown and described.

WALTER BAKER, JR.
